ENTERTAINMENT CENTER

DeWitt Y. Gorman, P.O. Box 23323,
Houston, Tex. 77032

Filed Aug. 26, 1970, Ser. No. 24,699

Term of patent 14 years

Int. Cl. D14—03

U.S. Cl. D26—14

FIG. 1 is an isometric view of an entertainment center showing my new design having a rectangular parallelepiped lower portion;

FIG. 2 is an isometric view of an alternative embodiment having a cylindrical lower portion; and

FIG. 3 is an isometric view of another alternative embodiment having a lower portion with a D-shaped horizontal cross section.

I claim:

The ornamental design for an entertainment center, substantially as shown and described.
